HOT WATER GENERATOR

Filed July 12, 1933

UNITED STATES PATENT OFFICE

1,967,706

HOT WATER GENERATOR

Joseph W. Carroll, Philadelphia, Pa., assignor to
 P. Carroll & Sons, Philadelphia, Pa., a copartnership composed of Edward P. Carroll and
 Joseph W. Carroll

Application July 12, 1933, Serial No. 680,023

7 Claims. (Cl. 257—238)

My invention has special utility as a hot water generator in which the heating medium is live or exhaust steam, or both, as may be convenient or necessary under the conditions of use; and 5 in construction is especially adapted as a heater for household and other domestic uses, wherein simplicity in design and relatively small size are desirable.

This application is in part a continuing application of my application Serial No. 614,423, filed May 31, 1932, which discloses a generator or water heater comprising a boiler-like tank or shell adapted to be normally maintained full of water under suitable pressure to insure circulation and delivery to the place of use. The tank, moreover, is provided with two heating means of different capacities, one of which is positioned near the inner bottom portion of the tank, and the other near the upper portion 15 thereof, said heating means adapted for separate or conjoint heating of the body of water within the boiler-like tank or shell and suitable for large production of hot water.

My present invention is intended as a water heating means of less capacity than the apparatus of my aforesaid application, and comprises a single heating means with similar steam circulating means but of lesser capacity than shown therein. Moreover, the heating means is 25 located wholly in the lower portion of the boiler-like tank or shell instead of being arranged in both the upper and lower portions thereof.

More specifically, the heating section arranged in the lower part of the boiler-like tank 30 or shell consists of a return tube construction in which there is a large tube closed at the inner end and having its outer or front end securely expanded and beaded within a heavy steel tube sheet, said closed tube constituting a jacket. 35 Inside of the said tubular jacket is provided a relatively smaller tube arranged to convey the heating steam to the extreme end of the water heating tube or jacket, through which the water of condensation returns to a condensate chamber 40 into which the large or jacket tube extends, thereby providing at all times removal of condensate and circulation of steam through the heating section. In this manner, the outer surface of the jacket tube becomes a direct heating 45 surface for its entire area, and the inner or steam delivery tube is insulated by the heated jacket or outer tube and will thereby retain the steam heat throughout its length and insure a supply of relatively dry steam to the closed end 50 of the outer or jacket tube, whereby the great-

est heating efficiency is secured. The front end of the inner tube extends through a head which constitutes a condensate receiving chamber from which the condensate may be drained through a suitable steam trap. The inner tube 60 communicates directly with a steam main and conveys the steam therefrom to the distant or inner end of the jacket tube from which the condensate returns along the annular passage formed between the inner steam tube and the outer jacket tube. Moreover, the inner steam tube is supported by the inner wall of the jacket tube and the latter is suspended by a bracket welded or otherwise secured to the inner wall of the boiler-like tank. Furthermore, the heavy 65 steel tube sheet to which the jacket tube is secured is bolted intermediate of a flanged outlet from the boiler-like tank and a flange of the head through which the inner steam tube extends and to which it is attached, whereby the 70 parts may be dismantled for cleaning or repairs, as may be necessary. The cold water supply piping connects with the boiler-like tank immediately below the jacket and steam tubes and is provided with a suitable branch or circulation 75 tube also connected with the bottom of the tank near the union of the jacket and steam tubes, whereby the heated water may be recirculated over the heating pipes and with the addition of cold water from time to time to compensate 80 for the hot water drawn off from the upper portion of the boiler-like tank for distribution 85 through the house and to the distant places, as may be required.

My improvements further consist of other features and details of construction which, together with those above referred to, are fully described hereinafter and pointed out in the claims.

The invention will be better understood by reference to the drawing, in which: Fig. 1 is a 90 vertical section on line 1—1 of Fig. 2, illustrating the general construction of the hot water generator embodying my invention; Fig. 2 is an end elevation of the same; Fig. 3 is a perspective view illustrating the manner of supporting 95 the inner steam tube within the outer jacket tube; and Fig. 4 is an enlarged view of the bushing and sweated joint shown in Fig. 1.

The generator tank 2 is made of any desired diameter and length to provide capacity to suit 100 the purpose for which the generator is designed. In general, the forward head 3 of the tank is provided near its lower part with a flanged port 7 somewhat larger than the outside diameter of the jacket tube 12, and the tank is fur- 105

ther provided near the flanged port with a feed water inlet 5 and at the top and near the rear head 4 with a hot water delivery outlet 6. The flanged port opening 7 is preferably made of a short length of tubing extending through the forward head 3 and electrically welded thereto as at 7b. The outer end of the port opening 7 is provided with a flange 7a which is preferably electrically welded at 7c. The heating tube or jacket 12 is provided at its inner end with a cap or head 34 which may be brazed or welded in any suitable manner. This cap is provided with an extending pin portion 35 which loosely fits into a hole 36 in a bracket 36a, the latter riveted or welded to the lower part of the tank and extending upwardly therein to provide a supporting means for the tube near the lower portion of the tank, whereby the tube may expand and contract freely. The outer end of the jacket or heating tube 12 is secured to a heavy steel tube sheet 9, the union being made by expanding the tube within the tube sheet and beating the end of the tube therein.

The inner or steam receiving tube 18, being insulated by the heated jacket or outer heating tube, will retain the heat throughout its entire length, and thereby insure the supply of relatively dry steam to the closed end of the outer or heating tube 12, whereby the greatest heating efficiency is secured. The front end 16, of the inner steam tube 18 extends through the condensate chamber 24 and is secured to the head 8 by a bushing 19. The tube sheet 9 and the flanges 7a and 8a are bolted together by means of bolts 11 and with gaskets 10 preferably interposed between the tube sheet 9 and the flanges 7a and 8a, to provide water tight but detachable connections for supporting the front or forward ends 20 of the tubes 12 and 18 and, at the same time, permit supply of steam to the inner tube and the discharge of condensate from the outer or jacket tube.

For simplicity in securing the outer end of the steam tube 18 to the condensate receiving head and also connecting it with a control valve 45, I prefer to employ a bushing 19 which is screw threaded on the outer surface so as to screw into the hub of the head 8 and made smooth on the inner surface to provide a sweated joint with the end of the inner tube 18, the outer threaded bushing also providing a threaded nipple 22 which may be screwed into and act as a support for the control valve 45 of any suitable construction (see Fig. 4). The other or inner end of the steam supply tube 18 is telescoped with the inner end of the outer or jacket tube 12 and permits longitudinal movement due to expansion and contraction; and to permit this operation between the tubes, the end of the inner tube 18 is centrally spaced by flanges 18a, as shown in Fig. 3. These spacing flanges 18a are shown as formed by radially flanging the ends of the inner tube 18 and employing a portion of the flanged parts to provide spacing between the end of the inner tube 18 and the interior wall of the outer or jacket tube 12. It will suffice to employ three or more of these spacing radial flanged portions 18a, though in practice I prefer four of such parts as shown for centralizing the end of the tube 18 within the closed end of the tube 12. The surplus portion of the flanged ends of the inner tube 18 is cut away so as to permit free passage of the steam through the inner tube into the outer tube 12, and thence with the water of

condensation through the annular space between the inner tube 18 and outer tube 12 back to the condensate chamber 24.

Where the steam passes from the inner tube 18 into the space 34a within the closed end of the jacket or outer heating pipe 12 is the hottest portion of this generator and acts to assist in the re-circulation of the water within the tank and also to impart the hottest condition of the water immediately below the hot water outlet, and thereby provide a speedy supply of hot water.

In the operation of my improved hot water generator, the steam is supplied through the valve 45 and pipe 18 to the distant end of the jacket or heating tube 12 in which it is condensed, with the liberation of the latent heat of the steam into the water contained in the tank 2, while the condensate from the condensed steam within the jacket pipe 12 is delivered from the condensate chamber 24 and thence passes through the pipe 24a to the steam trap (not shown). Normally, the water circulates over the heating pipes 12 and 18 and continues to re-circulate through house pipes 6 and return pipes 6a exterior to the tank 2 and connected with the interior of the same adjacent to the end and hottest portions of the heating pipes 12 and 18. The hottest portion of the tank 2 may be connected to the cooler portion thereof by a pipe 5a for the purpose of inducing a re-circulation within the tank to build up the heating temperature when the circulation of the hot water through the house pipes is at a minimum. This circulation is automatically maintained until the water within the tank affects the thermostatic control means 6b extending into the tank and which by the rising temperature of the water will cause the steam supply valve 45 to be throttled to reduce the heating effect of the steam upon the heating pipes 12 and 18.

A suitable air vent valve 53 and vacuum breaker valve 54 may be employed as a protection to the hot water generator for excessive variations in pressure or vacuum, and these elements may be respectively connected by elbow-shaped pipes 51 and 52 each communicating with the condensate chamber 24 of the head 8, as more particularly illustrated in Fig. 2.

The tank may also be provided with a hand hole 5x for cleaning purposes, and if arranged near the rear end of the tank, it may be employed to permit the entrance of the hand in guiding the projecting guide pin 35 of the pipe 12 into the bracket 36 when assembling the heating section in place within the tank. Furthermore, the tank may be provided with a mud blow-off pipe and valve shown at 55, and with a water relief valve as shown at 6c, of any suitable construction.

It will now be apparent that I have devised a novel and useful construction which embodies the features of advantage enumerated as desirable, and while I have in the present instance shown and described the preferred embodiment thereof which has been found in practice to give satisfactory and reliable results, it is to be understood that I do not restrict myself to the details stated as the same are susceptible of modification in various particulars, without departing from the spirit or scope of the invention.

I claim:

1. A hot water generator comprising, in combination, a horizontal closed tank provided on its interior with a heating section positioned near

the lower portion of the tank and consisting of a pair of inner and outer telescoped tubes arranged to form a return tube heating structure for steam and condensate, means for sup-

- 5 plying steam to one end of the inner tube, means for receiving water of condensation from said tubes and removing it from the generator, said outer tube being closed at its inner end and receiving steam at said end from the inner 10 tube, means within the tank for supporting the inner end of the outer tube, a flanged orifice in one of the heads of the tank and through which the telescoped heating tubes extend, a transverse tube sheet to which the outer end of 15 the outer tube is secured, said tube sheet fitting against the flange of the tubular outlet of the tank, a flanged head forming a condensate chamber having drainage means for condensate and to which the inner tube is secured, detach- 20 able bolt connections through the several flanges and tube sheet to support the heating tube section in fixed position within the lower portion of the tank, means for supplying cold water to the tank, and an outlet for hot water ar- 25 ranged in the upper portion of the tank and relatively above the juncture where the inner tube supplies steam to the closed end of the outer tube.

2. The invention according to claim 1, wherein 30 the tank is also provided with a hand hole ar- ranged in the wall of the tank at or near the level of the supported end of the closed outer tube.

3. The invention according to claim 1, wherein 35 the tank is also provided with a hand hole ar- ranged in the wall of the tank at or near the level of the supported end of the closed outer tube, and wherein further, the means for sup-

porting the inner end of the outer tube comprises a pin in alinement with the length of the tube and a bracket secured to the tank and having guiding means for the pin, said means being within reachable distance through the hand hole.

4. The invention according to claim 1, wherein further, an air vent valve and a vacuum breaker valve are respectively secured in communication with the sides of the condensate chamber of the head.

5. The invention according to claim 1, wherein further, the tank is provided with re-circulation tubes comprising piping arranged outside and below the tank and the heating structure herein.

6. A hot water generator comprising, in combination, a horizontal closed tank having a flanged tubular outlet from one end of the tank and close to the bottom thereof and a heating section composed of a pair of inner and outer tubes arranged in concentric relation having intercommunication at one end within the tank and separated at the other end outside of the tank and having the outer tube bolted to the tank and the inner tube screwed into a detachable head bolted to the flange of the outer tube, said tubes being telescoped one with respect to the other.

7. The invention according to claim 6, wherein further, the hot water pipe from the tank connects with it at its upper portion and the heating section is arranged within the tank adjacent to its bottom and approximately below the connection of the hot water pipe with the upper part of the tank.
